DESIGN FOR A DRESS AND SLIP ENSEMBLE

Alice Engel, New York, N. Y.

Application January 19, 1939, Serial No. 82,426

Term of patent 3½ years

To all whom it may concern:

Be it known that I, Alice Engel, a citizen of the United States, residing in New York city, in the county of New York and State of New York, have invented a new, original, and ornamental Design for a Dress and Slip Ensemble, of which the following is a specification, reference being had to the accompanying drawing, forming part thereof.

Fig. 1 is the front view of a dress and slip ensemble showing my new design, and

Fig. 2 is the rear view thereof.

The characteristic features of my design reside in the combination on the specific dress and slip ensemble disclosed of the specific bow trimmed, Shirred dress bodice and the specific ribbon and bow trimmed, flounced slip, which latter detail is visible through the transparent dress skirt, the slip bows and ribbons matching those on the dress bodice as shown.

I claim:

The ornamental design for a dress and slip ensemble, substantially as shown and described.

ALICE ENGEL.
